TANK CAR

Karl S. Howard, St. Louis, Mo., assignor to General Steel Castings Corporation, Granite City, Ill., a corporation of Delaware

Application May 15, 1931, Serial No. 537,721

7 Claims. (Cl. 105—358)

This invention relates to railway rolling stock and consists particularly in novel construction of tank cars, tenders, and the like.

Tank cars and tenders of ordinary types of construction are usually provided with center or side sills, or both, for transmitting longitudinal forces from end to end of the car, which sills carry the load and transmit pulling and buffing stresses. If located inside the tank, such sills materially decrease the tank capacity and, if located outside the tank, they raise the center of gravity of the car.

The elimination of center and side sills, if possible, would obviously materially reduce the weight and cost of the car and also permit increased tank capacity and lower center of gravity. The main object of my present invention is to provide a tank car structure in which the cylindrical tank alone, without abnormal reinforcement, will be of sufficient strength to resist longitudinal as well as vertical forces between the bolsters.

I attain this object and others hereafter appearing in the structure illustrated in the accompanying drawings in which—

Figure 1 is a horizontal end section taken on the center of the tank of a car embodying my invention.

Figure 2 is a vertical longitudinal section taken on line 2—2 of Figure 1.

Figure 3 is a side elevation of the other end of the car.

Figure 4 is an end elevation of the car.

Figure 5 is a vertical transverse section taken on line 5—5 of Figure 1.

Figure 6 is a horizontal end section corresponding with Figure 1 and showing a modified form of my invention.

Figure 7 is a vertical longitudinal section taken on line 7—7 of Figure 6.

Figure 8 is a vertical longitudinal section corresponding with Figure 7 and showing another modification.

Figure 9 is a detail vertical transverse section taken on line 9—9 of Figure 8.

Figure 10 is a detail vertical transverse section taken on line 10—10 of Figure 8.

Figure 11 is a horizontal section corresponding with Figures 1 and 6 and illustrating still another modification.

Figure 12 is a vertical longitudinal section taken on line 12—12 of Figure 11.

Figure 13 is a detail vertical transverse section taken on line 13—13 of Figure 12.

In Figures 1 to 5, I show a tank composed of a main cylindrical portion 1 which is closed at both ends by dome shaped end sections 2. The tank

is supported beneath each end by a combined bolster and draft sill casting which rests upon a truck not shown in detail, but indicated by wheels 3. Each supporting casting includes draft sills 4 and box shaped bolster 5, the latter having the usual jacking pads 9 at each end. An enlargement 7, having a central perforation, is provided in the center of the bottom web of the bolster for receiving the usual center plate (not shown), but the top webs of both the bolster and the adjacent reinforcing structure 6 are imperforate, any holes provided to facilitate casting being welded closed by plates, such as that shown at 8, so that these webs may co-operate to form a portion of the bottom of the tank. Diagonal reinforcing ribs 10 extend across the corners between the outer vertical walls of the reinforcing structure 6 and draft sill 4.

Hand brake standards 11, ladders 12 and supporting brackets therefor, and brackets 13 for supporting running boards 14 may be welded, or riveted, or secured in any other suitable manner to the casting.

The main intermediate portion 1 of the tank is cut out at each end, as at 15, and the edges of the opening formed thereby rest upon curved flanges 16 and 17 which form a saddle extending around the body of bolster 5 and reinforcing structure 6. Flange 16 merges at its lowest point with the bottom web of the bolster and then curves upwardly and outwardly along the inner face of the bolster and at the top meets the upper flange 17. Flange 17 merges with the top web of the bolster and curves outwardly and upwardly therefrom in conformance with the contour of the adjacent portion of the tank and also extends outwardly from member 6 to provide a support for tank end member 2. The tank sheets are preferably welded to the saddle forming flanges 16 and 17 to form a water tight tank bottom.

Hand rail brackets 18 and additional running board supports 19 may be secured to the tank sheet by studs or rivets in the usual manner.

In Figures 6 and 7, a separate tank section 20 has an opening in its lower surface for receiving the bolster and draft sill casting indicated generally at 21. The inner portion 22 of the tank supporting saddle is elongated and reinforced by ribs 23 for more effectively transmitting longitudinal forces to the tank sheet. The end member 24 and tank sections 20 and 25 are welded to saddle forming flanges 22 and 26, respectively, as in the form previously described.

In Figures 8 to 10 the tank sheet 27 is continuous to the tank end 31, there being no opening 55

therein filled by the bolster and draft sill casting. The bolster 28 and the inner end of the inverted U-section draft sill structure 33 are reduced in depth to provide increased tank capacity. The bolster top wall including extension flange 29 is secured to the tank and flanges 34 extending laterally from the intermediate portions of the draft sills 33 are also secured to the tank but the draft sills themselves are received in a recess formed 5 in the lower portion of the tank, there being a space between the top and the shouldered inner end of the draft sill structure and the bottom and end wall of the tank recess. Ribs 30 carry draft forces from the lower part of the bolster to the 10 flange 29 and the tank sheet. Longitudinal forces will thus be transmitted directly to the bolster and saddle before being transferred to the tank sheets so that stresses will be distributed over a 15 greater area.

20 In Figures 11, 12, and 13, the tank 40 is imperforate and of regular cylindrical shape throughout. The top surface of the bolster 35 at the middle is at the same level as the of draft sills 36 and portions of the upper surfaces 25 of both bolster 35 and draft sills 36 form portions of the supporting saddle 38. Saddle 38 is shaped to conform with the contour of the tank and ribs 39 are provided to reinforce the bolster and the inner part of the saddle. In this form the center 30 of gravity of the car is somewhat higher than in forms previously described.

It will be seen that in the structures disclosed all longitudinal forces are transmitted from the draft sills directly to the bolster and supporting 35 saddle through my novel integral casting, thence to the tank sheets, the tank thus forming the sole structural element between the end castings. Due to the fact that the supporting saddle is secured to a substantial portion of the tank sheet 40 and the latter are of substantially equal thickness, these forces are not limited to any particular part of the tank but are distributed gradually over the entire circumference of the tank and consequently no part of the tank need be particularly 45 reinforced. I have found that the sheets of ordinary size and thickness will adequately withstand all pulling and buffing stresses. The above disclosed structures attain the advantages of low center of gravity and maximum capacity 50 combined with substantial reduction in weight of the car and conformance with strength requirements without unusual reinforcement of the tank itself.

Obviously, the structures illustrated may be 55 varied as to other details without departing from the spirit of the invention and I contemplate the exclusive use of all such variations as come within the scope of my claims.

I claim:

- 60 1. In combination in a railway vehicle, a tank including a continuous wall and having an offset in the lower surface thereof, and structure separate from said wall and supporting said tank on each side of said offset and including a bolster, 65 a draft sill, and a saddle forming flange engaging said tank, a portion of the top of said bolster being depressed below the level of the upper surface of said draft sill, and respective portions of said flange merging with the upper surface of said 70 bolster and a portion of said draft sill spaced beneath the top thereof.

2. In combination in a railway vehicle, a draft sill, a bolster, the upper middle portion of which is below the level of the top of said draft sill, a tank carried on and secured to said bolster and extending forwardly therefrom and having a recess in its lower portion to provide a space between the tank and the draft sill.

3. In combination in a railway vehicle, a tank forming a longitudinal force transmitting element of the vehicle and an integral casting supporting said tank at one end and including a draft sill and a bolster, the bolster having a top element extending partially around and being secured to a substantial portion of the surface of said tank for transmitting longitudinal forces thereto, said tank being recessed over said draft sill and said bolster element constituting the sole longitudinal force transmitting connection between said tank and said casting.

4. In combination in a railway vehicle, a tank 20 forming the sole longitudinal structural element of said vehicle, and an integral casting supporting said tank at one end and including a draft sill, a bolster, and a saddle forming flange extending partially around and being secured to 25 a substantial portion of the surface of said tank for transmitting longitudinal forces thereto, said tank being recessed over said draft sill, longitudinal forces being transmitted from said draft sills solely through said bolster and said flange and 30 then distributed over a substantial portion of the wall of said tank.

5. In combination in a railway vehicle, an imperforate tank having a reduced end portion forming an offset in the lower surface thereof, 35 and an integral casting supporting said tank on each side of said offset and including a bolster, a draft sill, and a saddle forming flange engaging said tank, said flange and the upper surface of said bolster being shaped to conform in general 40 with the contour of the adjacent portion of said tank, and the central portions of said flange and bolster being depressed beneath the upper surface of said draft sill.

6. In a railway tank vehicle, an end casting 45 including draft sill structure of inverted U-section and bolster members projecting laterally therefrom, and a complete tank structure supported at one end on said casting and having a continuous wall independently of said casting and 50 recessed longitudinally to overlie the top of said draft sill structure, said tank structure constituting the sole means for connecting said end casting to the opposite end of the vehicle.

7. In a railway tank vehicle, an end casting 55 including draft sill structure of inverted U-section and bolster structure extending transversely of said draft sill structure, the upper central portion of said bolster structure being at a lower level than the top of said draft sill structure, and a complete 60 tank structure supported at one end on said end casting and having a continuous wall independently of said casting and recessed transversely and longitudinally to form a pocket fitting over the rear end and side corners of said draft sill 65 structure, said tank serving as the sole means for transmitting longitudinal forces from said end casting to the opposite end of the vehicle.
